(57) **CLAIM**

The ornamental design for a vehicle fog lamp, as shown and described.

DESCRIPTION

FIG. 1 is a front perspective view of a vehicle fog lamp illustrating the new design.

FIG. 2 is front view thereof.

FIG. 3 is left side view thereof.

FIG. 4 is right side view thereof.

FIG. 5 is rear view thereof.

FIG. 6 is top view thereof; and,

FIG. 7 is bottom top view thereof.

The lamp in use is viewable only from the front. In all of the foregoing drawings, dashed lines are exemplary of hidden lines, intended to illustrate shape and contour and are not part of the design.
